DESIGN FOR A COMBINATION STOVE AND
REFRIGERATOR UNIT

Charles S. Balkman, Pittsburgh, Pa.

Application May 1, 1946, Serial No. 129,174

Term of patent 14 years

(CL. D81—4)

To all whom it may concern:

Be it known that I, Charles S. Balkman, a citizen of the United States, residing in Pittsburgh, in the county of Allegheny and State of Pennsylvania, have invented a new, original, and ornamental Design for Combination Stove and Refrigerator Unit, of which the following is a specification, reference being had to the accompanying drawing, forming part thereof.

Fig. 1 is a perspective view of a combination stove and refrigerator unit, showing my new design.

Fig. 2 is a vertical sectional view taken through the peripheral band on the upper walls of the article shown in Fig. 1.

I claim:

The ornamental design for a combination stove and refrigerator unit, as shown and described.

CHARLES S. BALKMAN.
